UNITED STATES PATENT OFFICE.

CARL JOHN FALK, OF MANISTEE, MICHIGAN.

RED, WHITE, AND BLUE GAME.

1,160,586.

Specification of Letters Patent. Patented Nov. 16, 1915.

Application filed July 31, 1915. Serial No. 42,880.

To all whom it may concern:

Be it known that I, CARL J. FALK, a citizen of the United States, residing at Manistee, in the county of Manistee and State of Michigan, have invented certain new and useful Improvements in Red, White, and Blue Games, of which the following is a specification.

The present invention relates to certain new and useful improvements in games, and has for its object to provide a device of this character which is peculiarly adapted for use in schools, since it embodies novel features of construction whereby provision is made for the mental and physical training of the players.

Further objects of the invention are to provide a game which is comparatively simple and inexpensive in its construction, which will hold the interest of the players, which will tend to develop both the minds and the bodies of the players, and which can be used in different manners.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:

Figure 1 is a side elevation of a board having the men set up thereon in the position assumed when starting to play the game, portions of the board being broken away. Fig. 2 is a top plan view of the same.

Corresponding and like parts are referred to in the following description and indicated in all the views of the drawing by the same reference characters.

Specifically describing the present embodiment of the invention, the numeral 1 designates a board upon which the men may be set up when playing the game, although it will be understood that no particular form of board is necessary, and that if desired the game can be played upon the sidewalk or directly upon the ground. A series of seven men 2 are lined up at one end of the board, the men having a distinctive color and being shown in the present instance as being red. A set of similar men 3 are lined up at the opposite end of the board in an opposed relation to the men 2, the men 3

also having a distinctive color and being shown in the present instance as blue. These men 2 and 3 are turned from wood, being somewhat similar in size and shape to Indian clubs, so that they are adapted to be used as such for exercising. Arranged in front of the red men 2 is a larger red man 4 termed the "colonel," and in a similar manner a blue "colonel" 5 is arranged in front of the blue men 3.

A white game piece or man 6 which carries a flag 7^a and is termed a "neutral" is placed between the two sets of men 2 and 3 so as to be substantially equidistant from both players. The players thus are designed to take positions behind the respective sets of men 2 and 3 and to toss the balls 7 of substantially the size and construction of standard baseballs back and forth, each player attempting to knock down the men or game pieces of the opposite player without knocking down the "neutral" game piece 6 which is placed at an intermediate point between the two sets of men. The player who first succeeds in knocking down all of the men and the "colonel" of the opposite side wins the game, although the game is considered to be lost by either player who may accidentally knock down the "neutral" game piece 6.

The game is particularly adapted for use in schools, and as a mental training the scholars would be encouraged to set up the men at different determined distances without the use of any measure. For physical training the men or game pieces 2 and 3 would be used in the same manner as Indian clubs, the scholars being caused to hold a man in each hand, stand erect, and exercise in different manners with the arms to strengthen and develop the muscles and lungs. As a game the device is played by two parties or sides, one side using the red men and the other side the blue men, and the men can be set up in various ways, each side attempting to knock down the men and "colonel" of the opposite side without knocking down the "neutral" game piece 6.

Having thus described the invention, what I claim as new and desire to secure by Letters Patent, is:

1. A game including two sets of distinctively colored game pieces adapted to be set up in opposed lines, a larger game piece 110 termed a "colonel" for each set of game pieces, a "neutral" game piece adapted to

be arranged at an intermediate point between the opposed lines of the two sets of game pieces, and a ball adapted to be thrown back and forth, each side attempting to knock down the game pieces and the "colonel" of the opposite side without knocking down the "neutral" game piece.

2. A game including two sets of distinctively colored game pieces turned from wood and having handles at the upper ends thereof so that they can be used for exercising, said game pieces being adapted to be set up in opposed lines, a larger game piece termed a "colonel" for each set of game

pieces, a "neutral" game piece adapted to be set up at an intermediate point between the two sets of game pieces, and a ball adapted to be thrown back and forth, each side attempting to knock down the game pieces and "colonel" of the opposite side without knocking down the "neutral" game piece.

In testimony whereof I affix my signature in the presence of two witnesses.

CARL JOHN FALK.

Witnesses:

CHAS. DAHLQUIST,
